INVENTOR
FERNAND CARBENAY
BY *Frank Adams*
ATTORNEY

UNITED STATES PATENT OFFICE.

FERNAND CARBENAY, OF PARIS, FRANCE.

TRANSFORMER FOR AMPLIFIER DEVICES.

Application filed May 17, 1923, Serial No. 639,701, and in France June 1, 1922. Renewed August 3, 1928.

The present invention relates to a novel method of building transformers of the kind used in combination with high frequency current amplifiers.

Transformers are already known of the ferro-magnetic core type which serve for insuring connection between the grid or the plate circuit of a three-electrode tube and the external circuit (plate or grid circuit of the three-electrode tube of the neighboring stage, or input or output circuit of the amplifier tube). In the construction of these transformers, one chief aim is to eliminate the capacity between the primary and the secondary windings, and with this end in view it has been the general practice to keep these windings spaced from each other by arranging each winding upon a cardboard cylinder placed upon the core, the two cylinders being of widely differing diameter in order to leave several millimeters clearance space between the two windings.

It is an object of this invention to produce a transformer of the type described having an appreciable capacity between its windings. It is another object to produce such a transformer which may be relatively simply and economically constructed. Still another object of the invention is to produce a transformer which shall operate efficiently over a wide range of wave lengths. Still other objects of the invention will be apparent from the specification which should be read in connection with the accompanying drawing in which:

Fig. 1 is a sectional view of a transformer constructed according to my invention, and Fig. 2 is a cross section on line 2—2 of Fig. 1.

Now, contradistinct from the prior practice, according to the present invention, an appreciable capacity is provided between the windings; for instance, one winds the two coils upon one another, each of them being preferably restricted to one layer (pile-winding) with the interposition, if necessary, of a sheet of paper or other insulating material of very great thinness. In this manner, the capacity between the windings is increased, and the result thereof is that the limits or range of frequencies for which the amplifier can be usefully employed, are enlarged in a very economical manner. The device when so constructed constitutes at the same time an inductive and capacitive coupling and the sum of the effects, which vary with wave

length changes in inverse sense, preserves a convenient value between the wide wavelength limits. At the higher range of frequencies for which the transformer is designed to be used as a coupling the capacitative features of the coupling predominate and at the lower frequencies the inductive features of the coupling predominate. At the intermediate frequencies the capacitative and inductive features coact in different degrees, the relation between the two being of course determined by the particular frequency. It will therefore be apparent that the effect of the frequency being used will tend to change the characteristics of the coupling in such a way as to better adapt it to the particular frequency.

For the proper operation of a transformer of the sort just described, it is necessary that a certain relationship and correspondence should be observed between the terminals of the windings. Inasmuch as both windings are assumed to be restricted to just one layer, and since both are wound in the same sense, the end of the primary connected with the plate of a triode must be upon the same side of the winding as the end of the secondary connected with the grid of the triode next following.

Referring now to the accompanying drawing 1 represents a hollow cylindrical casing, preferably of non-magnetic insulating material, closed at one end. The open end of the casing is closed by the cover 6 which may be of the same material as the casing itself. An iron core 5, shown as consisting of a bundle of iron wires, is supported axially of the casing in grooves 7 and 8 in the closed end and cover of the casing, respectively. It will be noted that a considerable air space is left between the iron core and the cylindrical walls of the casing.

On the outside of the cylindrical casing are wound the transformer coils 2 and 3 separated from each other by a thin sheet of insulating material 4, which may very well be a sheet of paper, the thickness being exaggerated in the drawing to make the illustration clear. These coils are mounted about midway of the ends of the casing and are shown as covering only a small portion of the area. It is to be understood that the form, constitution, and dimensions of the magnetic core are arbitrary, as are likewise the constants of the windings (number of turns, cross-sectional area of the wire, etc.), and

these factors can be varied in conformity with the purpose or service for which the device shall be used, and the effects that shall be produced. One of the most preferable plans 5 of building the core should be to make it of a bundle of very thin iron wires, conveniently annealed and possessing high permeability, and thus constituting a core of straight form. It should be noted that various arrangements 10 of windings adapted to obtain sufficient capacity between the primary and secondary windings may be utilized without departing from the spirit and idea underlying the present invention. For instance, the primary and 15 secondary windings can be wound simultaneously two wires in hand in a way so as to place their respective spires contiguous, etc.

Having described my invention, what I claim is:

20 1. A radio frequency coupling transformer comprising primary and secondary windings, one directly superposed on the other for increasing the capacity therebetween, a magnetic core consisting of a bundle of fine iron 25 wires of high permeability disposed centrally of the windings and spaced therefrom, said transformer windings being thereby adapted to progressively change the character of the

coupling from inductive to capacitive as the frequency changes from a lower to a higher 30 frequency within the operating range.

2. A high frequency transformer comprising primary and secondary windings, each consisting of a single layer and directly superposed one on the other for increasing the capacity therebetween, and a magnetic core composed of a bundle of very fine iron wires possessing high permeability disposed centrally 35 of the windings and spaced therefrom.

3. An arrangement for inductively and 40 capacitively coupling a pair of high frequency current amplifiers, comprising a centrally arranged magnetic core of very fine iron wires possessing high permeability, a primary winding arranged to be connected 45 to the output of one of said amplifiers disposed around said core and spaced therefrom, a secondary winding arranged to be connected to the input of the second of said amplifiers superposed on said primary, and a thin sheet of insulation disposed between both windings, whereby the character of the coupling is changed from inductive to capacitive as the frequency changes from a lower to a higher value within the operating range.

FERNAND CARBENAY.
